UNITED STATES PATENT OFFICE.

SIMEON LORD, OF PHILADELPHIA, PENNSYLVANIA, ASSIGNOR OF ONE-HALF
TO ENOS VERLENDEN, OF DARBY, PENNSYLVANIA.

PICTURE-HANGER.

SPECIFICATION forming part of Letters Patent No. 603,146, dated April 26, 1898.

Application filed October 15, 1897. Serial No. 655,337. (No model.)

To all whom it may concern:

Be it known that I, SIMEON LORD, of the city and county of Philadelphia, State of Pennsylvania, have invented a certain new and useful Improvement in Picture-Hangers; and I do hereby declare the following to be a full, clear, and exact description of the invention, such as will enable others skilled in the art to which it appertains to make and use the same.

The object of my invention is to produce a cheap, simple, and strong device for attaching the cord to picture-frames in such manner that said cord may be lengthened or shortened at will without taking the picture down from its hook and without releasing either end of the cord or wire from the picture.

In the drawings, Figure 1 is a rear elevation of a picture-frame, broken away, with my improved hanger attached. Fig. 2 is a side elevation of the winding-drum. Fig. 3 is a longitudinal vertical section of the drum.

In Figs. 1 to 3 I have illustrated my preferred form of hanger, in which *a* is a frame, broken away.

b is a hanger composed of a body portion the lower end of which is turned at right angles, as at *b'*.

b' are two diverging arms or supports extending from and integral with the upper portion of the support, each being provided with apertures near the end.

c is a spring winding-drum, to which is secured a ratchet-wheel *d*, said wheel being secured rigidly to said drum.

e is a bolt by means of which the drum and ratchet-wheel are secured to the hanger *b*, the drum and its ratchet being free to revolve on said bolt.

f is a pawl pivoted at *f'* to the support *b* and provided near its forward end with an aperture in which is secured a suitable operating-cord *h*, the lower end of which for convenience being secured to the frame by means of the screw-eye *h'*.

h is a coiled or other spring secured between the pawl and right-angled portion of the frame *a*.

I are two eyes secured to the frame. These screw-eyes, instead of being entirely closed, as heretofore, are provided with an opening

i, as clearly shown in Fig. 4, through which the cord or wire may be passed.

K is the cord, wire, or other suitable suspending medium, both ends of which are secured to the winding-drum at diametrically opposite points. The cord is then wound by the spring around the drum.

When it is desired to use the adjuster or hanger, it is secured to the frame by means of the screws *k*. After it is thus secured the cord or wire is then partially unwound from the reel or drum and passed through the openings *i* in the screw-eyes. The cord *h* is then secured, if desired, to the eye *h'*. The cord *h* is then pulled, thereby freeing the pawl from the ratchet-wheel, whereupon the hanging-cord *K* may be pulled out to the desired length, when the cord *h* is released and the pawl again engages the ratchet-wheel, thus locking the drum against rotation. After the picture is hung, if it is found that it is too high, the pawl *f* is again pulled out of engagement with the ratchet-wheel and the frame pulled down as far as desired. If, on the other hand, the picture is too low, it is only necessary to raise it in the hand, thereby taking the weight off the spring in the winding-drum, whereupon the spring will wind up the wire as long as the frame is so held. When the proper position is reached, the frame is released from the hand, thereby stopping the winding in of the cord.

The devices will be sold to the public with the wire wound upon the winding-drum, thus furnishing a complete picture-hanger ready for use. They will be made in various sizes, and the length of wire furnished will vary according to the size of the reel. For instance, a reel two inches in diameter will be supplied with eight feet of wire, three inches in diameter with twelve feet of wire, and so on.

What I claim, and desire to secure by Letters Patent, is—

1. In a picture-hanger, the combination of a spring-controlled winding-drum, a ratchet-wheel connected to said drum, with a frame on which to mount said drum and ratchet-wheel, a pawl pivoted on said frame and adapted to normally engage said ratchet-wheel and an operating-cord secured to said pawl, substantially as described.

2. In a picture-hanger, the combination with
a supporting-frame, diverging arms extending
from said frame, a right-angled portion
integral with the lower end of said frame, a
5 spring-controlled winding-drum mounted on
said frame, a ratchet-wheel connected to said
drum, a pawl pivoted to the frame and en-
gaging said ratchet-wheel, a spring seated on
the said right-angled portion under the pawl,
and a cord or wire secured to the forward end 10
of said pawl for operating the same.

SIMEON LORD.
